ATTORNEY

UNITED STATES PATENT OFFICE.

MARY GORRELL, OF BILLINGS, MONTANA.

BOBBIN.

1,243,157.

Specification of Letters Patent.

Patented Oct. 16, 1917.

Application filed February 1, 1916. Serial No. 75,573.

To all whom it may concern:

Be it known that I, MARY GORRELL, a citizen of the United States, residing at Billings, in the county of Yellowstone and 5 State of Montana, have invented certain new and useful Improvements in Bobbins, of which the following is a specification.

My invention relates to new and useful improvements in bobbins and more particularly to a tatting bobbin.

The primary object of the invention is the provision of a bobbin which may be worn upon the finger.

A further object of the invention is the 15 construction of a bobbin in such a manner that it will rotate easily so that the thread may be drawn therefrom.

A still further object of the invention is the provision of means for securing the 20 thread to the bobbin.

With these and other objects in view the invention consists in the novel details of construction and arrangement of parts which will be more clearly understood from 25 the following description and drawings, in which,

Figure 1 is a perspective view showing the bobbin held upon the finger.

Fig. 2 is a longitudinal vertical section 30 through the bobbin,

Fig. 3 is an end view of the bobbin,

Fig. 4 is a longitudinal vertical section through the rotatable portion of the bobbin, and

Fig. 5 is a longitudinal vertical section 35 through the axis of the bobbin.

In the drawings the numeral 1 indicates a cylinder which forms the axis of the bobbin and said cylinder is formed on each end 40 with an outwardly extending flange indicated at 2. The rotatable portion of the bobbin comprises a cylinder 3 which is of such a diameter that it will freely rotate upon the cylinder 1 and an upwardly extending flange 4 is formed on each end of the cylinder 3 and the cylinder 3 with the flanges 4 are received between the flanges 2 of the cylinder 1. The flanges 2 are of such a height as to prevent the cylinder 3 45 from being dislodged from the cylinder 1 and the flanges 4 may be of any desired height to accommodate the amount of thread which it is desired to use.

Perforations 5 are formed in one of the 50 flanges 4, as is more particularly shown in Figs. 3 and 4 of the drawings, and these

openings are used for securing the thread upon the bobbin.

In Fig. 1 of the drawings, the numeral 6 indicates the bobbin thread adapted to be 60 received upon the bobbin and 7 indicates the shuttle thread which is adapted to be tied to the bobbin thread, as indicated at 8.

Having fully described the details of construction it is thought that the operation 65 and advantages of my device will be clearly understood. In tatting it has been the usual custom to wrap a portion of the thread around the little finger of the left hand and it has been found that when the thread is 70 drawn it will tighten upon the finger and it is necessary to loosen the same and rewind. It is to overcome this difficulty that my invention is intended and the cylinder 1 is adapted to be placed over the little finger 75 of the left hand, as is clearly illustrated in Fig. 1 of the drawing. The bobbin thread is adapted to be wound upon the cylinder 3 between the flanges 4 and as the thread is drawn, the cylinder 3 will rotate upon the 80 cylinder 1. My bobbin is adapted to be used with the ordinary form of shuttle which forms no part of my invention. The thread is secured to the cylinder 1 by passing one end thereof through the openings 5 and 85 tying a knot in the same. The bobbin may be made of any desired material which will give sufficient strength thereto and when in use, the thread will be drawn around the various fingers, as is illustrated in the 90 drawings.

Having fully described my invention what I claim as new and desire to secure by Letters Patent is:

1. A tatting device adapted to be mounted 95 on one of the fingers of the user's hand and comprising a pair of cylinders, one of the cylinders being frictionally engaged with the finger to prevent rotation, the other cylinder being rotatably mounted upon the first 100 mentioned cylinder and provided with thread, and means for fixing one end of the thread.

2. A tatting device adapted to be mounted 105 on the fingers of the user's hand and including a pair of relatively thin cylinders rotatably associated, and a relatively narrow flange formed on each cylinder for permitting convenient reception in the space between the fingers.

3. A tatting device adapted for attachment to one of the fingers of the user's hand 110

and including a pair of cylinders extended over the finger, each being of relatively thin material for permitting convenient reception of the cylinders in the space between 5 the adjacent fingers.

4. A tatting device including an inner cylinder adapted for attachment to one of the fingers of the user's hand, an annular flange formed at each end of the cylinder, 10 a rotatable cylinder mounted on the said

first mentioned cylinder and embraced by the said end flanges, and a relatively narrow flange formed on each end of the said rotatable cylinder.

In testimony whereof I affix my signature 15 in presence of two witnesses.

Mrs. MARY GORRELL.
